UNITED STATES PATENT OFFICE.

EDWIN LANE, OF NEW YORK, N. Y., ASSIGNOR TO CAROLYN LAUNDRY, OF NEW YORK, N. Y., A CORPORATION OF NEW YORK.

MARKER.

Application filed December 19, 1923. Serial No. 681,637.

To all whom it may concern:

Be it known that I, EDWIN LANE, a citizen of the United States, residing at New York, in the county of New York and State 5 of New York, have invented new and useful Improvements in Markers, of which the following is a specification.

This invention relates to markers for identifying individual pieces or articles and 10 groups of the latter of the same ownership prior and subsequent to launder and dry cleaning operations. The present invention particularly relates to a further development or an improvement of the marker 15 structures disclosed by my copending applications executed and filed of even date here-with. The primary object of the present improvement is to provide a marker of the class specified of a very simple form and 20 having means for detachably engaging a portion of an article or piece to be cleaned with positiveness and reliability and without injury to the said article or piece during launder or cleaning operations, and to 25 embody as a part of the complement thereof a sliding member for effecting a closure of the means for engaging a portion of the article or piece to prevent accidental detachment of the latter during strenuous 30 launder or cleaning operations and requiring a manual adjustment of the said sliding member to effect a detachment of the article or piece to which the marker may be applied. A further object of the invention is to provide 35 a marker having normally open clamping or engaging means for application to an article or piece to be laundered or cleaned and a device carried as a part of the marker to close the said clamping means with a 40 tight biting action relative to the article or piece placed in engagement therewith and incidentally to embody as a part of the marker a lock to prevent the clamping means from accidentally loosening or re- 45 leasing their grip relatively to the portion of the article or piece applied thereto. With these and other objects and advantages in view, the invention consists in the 50 construction and arrangement of the improved marker in its preferred and modified forms hereinafter more fully described and claimed.

In the drawing:—

Fig. 1 is a perspective view of a marker 55 embodying the improved features of the in-

vention and shown applied and locked to a portion of an article or piece adapted to be laundered or dry cleaned.

Fig. 2 is a central longitudinal vertical section of the marker. 60

Fig. 3 is a top plan view of the improved marker.

Fig. 4 is a detail perspective view of a modified form of the marker.

Fig. 5 is a longitudinal vertical section of the marker shown by Fig. 4 taken to one side of the center thereof. 65

As shown by Figs. 1, 2 and 3, the improved marker embodying the present features of invention consists of a doubled strip 5 of suitable non-corrosive metal, such as brass or phosphor-bronze, which is intermediately bent to form jaws 6 and 7, the bent extremity of the marker being of greater width than the jaws 6 and 7 to form 70 a bend 8 having thereon an identifying character 9. The jaw 6, for instance, adjacent to its free end has a plurality of indentations 10 and in opposition to these indentations the jaw 7 is formed with a plurality of openings 11 to receive the inward maximum projecting portions of said indentations, the indentations 10 and the openings 11 forming interacting retention means which extend transversely of the two jaws to engage a 75 portion of an article or piece therebetween and whereby said article or piece will become firmly attached between the jaws and be prevented from loosening or accidentally disengaging itself during launder or cleaning operations. The jaw 7 is longer than the jaw 6 to facilitate application of the free ends of the jaws to an article or piece 80 to be laundered or cleaned, and in the projecting portion of the jaw 7 a slot 12 is 85 formed and which serves as a hanging means to engage a hook, nail or other device on a wall or rack during certain temporary operations pursued in laundering and cleaning a piece or article, and whereby also 90 pieces or articles may be disposed in convenient position and rendered readily accessible for subsequent assortment into groups of pieces or articles having the same ownership. The jaw 6 is formed with a 95 spring locking tongue 13 which normally projects outwardly from the jaw at a suitable distance in rear of the indentations 10 and embracing the two jaws 6 and 7 is a slide 14 which is movable from a point in 100

105 groups of pieces or articles having the same ownership. The jaw 6 is formed with a 105 spring locking tongue 13 which normally projects outwardly from the jaw at a suitable distance in rear of the indentations 10 and embracing the two jaws 6 and 7 is a slide 14 which is movable from a point in 110

rear of the locking tongue or means 13 or between the latter and the head 8 forwardly over the said tongue to maintain the jaws in closed position and against accidental 5 opening movement. The locking tongue or means 13 as shown is of triangular form with the point or apex extremity thereof positioned centrally and directed towards the indentations 10, and when the slide 14 is 10 moved over said tongue the pointed end springs up in engagement with the rear edge of the slide, as shown by Fig. 1. When it is desired to release the jaws the operator presses the tongue 13 inwardly so that the 15 slide 14 may be moved rearwardly thereover. As shown by Fig. 2 one member of the head 8 has an indentation 15 projecting inwardly and engaging the opposite member of the head as a supporting resisting means to prevent the two members of 20 the head from being crushed or forced together a closer distance than that predetermined in the first construction of the improved marker. It is also preferred that a 25 part of the indentations and the corresponding openings 11 be made larger than the remaining portion thereof as clearly shown by Fig. 3, this same structure being embodied in Fig. 1 and the purpose of this 30 differentiation of the dimensions in the indentations and openings is to give a stronger bite and greater holding effect on the portion of the article or piece placed between the jaws, particularly a heavy article, 35 and thereby set up just as effective securing of the article or piece of a heavy character to the marker as will ensue by engagement of the marker with a light piece or article such as a handkerchief.

40 Figs. 4 and 5 illustrate a modification of the preceding structure and in this instance a single strip 16 of metal is provided and has at one end a head 17 bearing an identifying character 18, the main portion of this 45 modified marker being in the form of an elongated shank 19 which is narrower than the head 17 and has at the free end thereof a slot 20 for hanging purposes as explained in connection with the slot 12 of the form 50 first described. The shank 19 has a spring locking tongue 21 formed centrally therein and of triangular form and movable on the said shank is a slide 22, the slide and locking tongue being in all respects similar to the tongue 13 and slide 14 hereinbefore 55 specified. Between the tongue 21 and the slot 20 the shank is formed with two locking jaws 23 and 24 cut from the metal thereof and struck upwardly so that they 60 are normally open, the respective jaws having angular clamping heads 25 and 26 connected to their shanks by angular bends 27 to give the heads a maximum depression 65 relatively to the openings 28 and 29 formed in the shank. The jaw 23 with its head 25

is larger or has greater dimensions than the jaw 24 and head 26, and the opening 28 is also correspondingly increased in size, the object of this difference in dimensions of the two jaws being the same as that described in connection with the varying dimensions of the indentations 10 and openings 11, or so that relatively heavy articles may be firmly attached to the marker without liability of accidental disengagement 70 therefrom. The slide 22 performs the additional function in the present instance of compressing the jaws 23 and 24 and their respective heads 25 and 26. When a portion of a piece or article is inserted between the heads 25 and 26, and the adjacent portions of the jaws 23 and 24, the slide 22 is pushed forwardly over the shank 19 past the tongue 21 and engages the said jaws and compresses the latter and causes the said heads 75 thereof to enter the openings 28 and 29, and owing to the angular bends 27 the said heads 25 and 26 will be given a maximum depression within the openings 28 and 29 and firmly lock the portion of the article or 80 piece engaged thereby to the marker. This modified form of the marker may be readily released by depressing the tongue 21 and moving the slide 22 backwardly to release 85 the jaws 23 and 24.

90 In the present improved form of the marker the two jaws forming the essential attaching components are normally open, there being two jaws controlled by the slide 14 in the form of the device shown by Figs. 1, 2 and 3, and two jaws controlled by the slide 22 in the form of the device shown by Figs. 4 and 5, and in both forms of the device, the slide and locking tongue are embodied in the marker organization. It is 95 obvious that less material will be required in making the form of marker shown by Figs. 4 and 5 than in constructing the marker shown by Figs. 1, 2 and 3 with a corresponding reduction in the cost of manufacture.

100 The improved marker in its two forms hereinbefore described may be modified in its proportions, dimensions and minor details of construction without departing from the spirit of the invention or the scope of 110 the appended claims.

115 What is claimed as new is:—

1. A reusable metal laundry marker consisting of a strip of resilient metal having jaws provided with angularly disposed fabric impenetrating projections, the projections being positioned relatively to openings to receive them and the fabric engaged by the projections, a part of the impenetrating projections and openings being of 120 less dimensions than the remaining part thereof to give a stronger bite and greater holding effect on the fabric engaged by the projections, and means shiftable carried by the marker for temporarily forcing the pro- 125

130

jections into the openings and also operable to release said projections from the openings.

2. A reusable metal laundry marker consisting of a strip of resilient metal having 5 jaws provided with angularly disposed fabric impenetrating projections, the projections being positioned relatively to openings to receive them and the fabric engaged by the projections, the impenetrating projections and openings being of different dimensions to give a stronger bite and greater holding effect on the fabric engaged by the projections, the marker also having an outwardly projecting resilient locking device 10 in rear of the projections, said resilient locking device being manually depressible, and shiftable means carried by the marker for temporarily forcing and holding the projections in the openings and movable over 15 and engageable by said locking device, the shiftable means also being operable to release said projections from the openings.

3. A reusable marker of the class specified, consisting of a doubled flat strip of spring 20 metal to provide permanently opposed flat spring jaws which are normally open, the jaws extending from rear flat body portions of the marker having means in advance of the bend of strip for preventing complete 25 closure of one portion relatively to the other and also provided with an identifying character, the jaws being respectively formed with fabric impenetrating projections and 30 relatively positioned openings to receive the projections, the openings and projections being all located in advance of the body portions 35 of the marker and in rear of the free ends and also between the opposing sides of the jaws, the projections and openings there- 40 for being in groups of different sizes, and shifting means embracing the body portions and movable over the jaws for temporarily forcing the projections into the openings and to hold the jaws closed, the shifting means 45 also being operable to release the projections from the openings.

4. A reusable marker of the class specified consisting of a doubled strip of flat spring metal to provide a permanently shaped body 50 having smooth flat members extending forwardly from the bend, the flat members hav-

ing spring jaws continuing therefrom and adapted to be closed, the flat body members being held in spaced relation when the jaws are closed, the one jaw having inwardly and 55 rearwardly extending blunt projections and the other jaw having relatively positioned openings to receive the said projections, the projections and openings of the two jaws being arranged in rows and the respective rows 60 of different sizes and all located in advance of the flat body members and also inwardly a distance from the free ends of the jaws and between the opposite side edges of the jaws, and shifting means on the jaws and flat body 65 members for temporarily forcing the projections into the openings and also operable to release said projections from the openings.

5. A reusable marker of the class specified 70 consisting of a doubled strip of flat spring metal to provide a permanently shaped body having smooth flat members extending forwardly from the bend, the flat members having flat spring jaws continuing therefrom and adapted to be closed, the flat body members being held in spaced relation when the jaws are closed, the one jaw having inwardly and 75 rearwardly extending blunt projections and the other jaw having relatively positioned openings to receive the said projections, the projections and openings of the two jaws being all located in advance of the flat body members and also inwardly a distance from the free ends of the jaws and between the opposite side edges of the jaws and 80 having a transverse row arrangement, the one body member in rear of the projections and openings of the jaws having a resilient locking device normally standing outwardly 85 therefrom and manually depressible into the body member, and means longitudinally shiftable over the body members and the jaws and the said locking device which engages the rear edge of said shiftable means to retain the jaws closed and force the projections into the openings, the locking device being operable to release the said latter 90 means and free the projections from the openings.

In testimony whereof I have hereunto set 100 my hand.

EDWIN LANE.
